(57) **ABSTRACT**

A ladder system includes a ladder having a ladder top, the ladder top having at least a first slot. A container having at least a first protrusion that engages with the first slot to hold the container to the top. A method for working from a ladder. The method includes the steps of filling a container with objects and engaging a first protrusion of the container with a first slot of a top of the ladder to hold a container to the top.

FIG. 5

FIG. 6

FIG. 9

FIG.10

1

TRADE BASED COMPONENT CASE AND LADDER BUCKET

CROSS-REFERENCE TO RELATED APPLICATIONS

This is a divisional application of U.S. patent application Ser. No. 11/449,457 filed Jun. 7, 2006, now U.S. Pat. No. 8,453,796 issued on Jun. 4, 2013, incorporated by reference herein.

FIELD OF THE INVENTION

The present invention is related to a ladder having a container that attaches to a top of the ladder. More specifically, the present invention is related to a ladder having a component case or a ladder bucket that attaches to a top of the ladder.

BACKGROUND OF THE INVENTION

Professionals use containers for their tools and small parts. The problem they have is for the tools and small parts in the container to be readily available to them when they are working while on a ladder.

BRIEF SUMMARY OF THE INVENTION

The present invention pertains to a ladder system. The system comprises a ladder having a ladder top. The ladder top has at least a first slot. The system has a container having at least a first protrusion that engages with the first slot to hold the container to the top.

The present invention pertains to a method for working from a ladder. The method comprises the steps of filling a container with objects. There is the step of engaging a first protrusion of the container with a first slot of a top of the ladder to hold the container to the top.

BRIEF DESCRIPTION OF THE SEVERAL VIEWS OF THE DRAWING

In the accompanying drawings, the preferred embodiment of the invention and preferred methods of practicing the invention are illustrated in which:

FIG. 1 is a schematic representation of the case of the present invention.

FIG. 2 is a schematic representation of the case.

FIG. 3 is a schematic representation of the case and a ladder top.

FIG. 4 is a schematic representation of the case and the ladder top.

FIG. 5 is a schematic representation of the bucket of the present invention.

FIG. 6 is a schematic representation of the bucket.

FIG. 7 is a schematic representation of a protrusion of the case or bucket.

FIG. 8 is a schematic representation of a slot of the top which receives the protrusion.

FIG. 9 is a schematic representation of a ladder with a case.

FIG. 10 is a schematic representation of a ladder with a bucket.

DETAILED DESCRIPTION OF THE INVENTION

Referring now to the drawings wherein like reference numerals refer to similar or identical parts throughout the

2

several views, and more specifically to FIGS. 3, 5, 9 and 10 thereof, there is shown a ladder system 100. The system 100 comprises a ladder 25 having a ladder top 11. The ladder top 11 has at least a first slot 8a. The system 100 has a container 75 having at least a first protrusion 3a that engages with the first slot 8a to hold the container 75 to the top 11.

Preferably, the container 75 has a handle 5. The top 11 preferably has a second slot 8b, and the container 75 has a second protrusion 3b which fits in the second slot 8b.

10 Preferably, each slot has a diameter which is smaller at its bottom than at its top, and each protrusion has a diameter which is smaller at its bottom than at its top. Each slot is preferably disposed at an edge of the top. Preferably, each protrusion is disposed at a first side 30 of the container 75. 15 The container 75 preferably has a second side 32 in parallel with the first side 30, a third side 34 connected with the first and second sides 30, 32 and a fourth side 36 in parallel with the third side 34 and connected with the first and second sides 30, 32.

20 Preferably, the sides form a rectangular shape. The ladder 25 is preferably a stepladder. The container 75 can be a case 50. The case 50 preferably has a lower section 1 and an upper section 2. Preferably, the upper section 2 is pivotally connected to the lower section 1. The handle 5 is preferably

25 connected to the upper section 2. Preferably, on the third side 34 is a first clasp 4a, and on the fourth side 36 is a second clasp 4b which lock the first and second portions together. The container 75 can be a bucket 9. Preferably, the handle 10 extends from the third side 34 and the fourth side 36. The 30 container 75 having a top 101 with an opening 103 which defines a container plane 105. The periphery of the ladder top 11 at the ladder top's top 111 defining a ladder top plane 113. The container plane 105 and the ladder top plane 113 in alignment and alongside each other to define an overall plane 115 when the first protrusion of the container 75 is engaged with the first slot of the ladder top 11.

35 The present invention pertains to a method for working from a ladder 25. The method comprises the steps of filling a container 75 with objects. There is the step of engaging a first protrusion 3a of the container 75 with a first slot 8a of a top 11 of the ladder 25 to hold the container 75 to the top.

40 Preferably, the engaging step includes the step of engaging a second protrusion 3b of the container 75 with a second slot 8b of the top 11 of the ladder 25 to hold the container 75 to the top 11. There is preferably the step of carrying the container 75 by its handle 5 up the ladder 25. Preferably, the container 75 is a case 50, and there is the step of opening an upper portion 2 of the case 50 to access the objects in a lower portion 1 of the case 50.

45 The new component case 50 and ladder bucket 9 of the present invention allow the user a place to store all of these items while providing a secure storage at the top of the ladder 25. The component case 50 and ladder bucket 9 can be filled with all of the tools and materials necessary and 50 then quickly and easily fastened high up on the ladder 25. This makes multiple trips up and down the ladder 25 unnecessary.

55 The component case 50, as shown in FIG. 1, consists of a lower section 1 and an upper section 2. The two sections 1, 2 are connected at the pivot point, as shown in FIG. 2. Attached to the middle of the upper lid section 2 is a handle 5. On each side of the case 50 are clasps 4a, 4b that lock the two portions together.

60 The two protrusions 3a and 3b side into ladder top slots 7, as shown in FIG. 4. The protrusions 3a, 3b fit into the corresponding slots 8a, 8b on the top. The slots 8a, 8b on the top are in the previous Electrician's and Pipe Trade Step-

3

ladder patent applications having U.S. patent application Ser. Nos. 11/358,626 and 11/416,967, respectively, incorporated by reference herein. The protrusions **3a**, **3b** firmly wedge into the slots **8** on the top. The weight of the case **50** is then supported by the protrusions **3** in the slots **8** and by resting on the front of the ladder top **11**.

The ladder bucket **9**, as shown in FIG. **5**, is a plastic bucket shaped container with protrusions similar to those on the component case **50**. The plastic bucket **9** has a handle **10** that can be used to carry the bucket **9** to the top of the ladder **10** **25** where it will be attached.

The two protrusions **3a** and **3b** slide into ladder top **11**, as shown in FIG. **4**. The protrusions fit into the corresponding slots on the top **8a**, **8b**. The protrusions **3a**, **3b** firmly wedge into the slots **8** on the top. The weight of the bucket **9** is then supported by the protrusions **3** in the slots **8** and by resting on the front of the ladder top **11**. **15**

The male protrusion **3** is shaped to fit the female geometry **8**. The protrusion **3** has a tapered shape **12**. The feature is larger at the top **17** and gets smaller near the bottom **18**. The female feature **8** is designed with a taper **14** that will fit the male feature **3**. The female feature is larger at the top **15** and gets smaller at the bottom **16**. The feature **8** also is designed with a lead in **13** to guide the male protrusion **3** into the slot **8**. **20**

Although the invention has been described in detail in the foregoing embodiments for the purpose of illustration, it is to be understood that such detail is solely for that purpose and that variations can be made therein by those skilled in the art without departing from the spirit and scope of the invention except as it may be described by the following claims. **25**

The invention claimed is:

1. A method for working from a ladder comprising the steps of: **30**
filling a container with objects, the container having a top with an opening which defines a container plane; and **35**

4

engaging a first protrusion extending vertically with respect to the top of the container with a first slot extending vertically with respect to the ladder top to hold the container to the ladder top, the ladder top having a periphery and a front with a front facing edge and a rear in spaced relation to the front and essentially in parallel with the front, the front essentially in parallel and disposed over a front section of the ladder, the rear essentially in parallel and disposed over a rear section of the ladder, the ladder top having the first slot having an opening in the periphery disposed on the front facing edge, the front section having a plurality of rails and rungs and the rear section having a plurality of rails and rungs, the rails of the front section directly attached to the ladder top and the rails of the rear section directly attached to the ladder top, the periphery of the ladder top at the ladder top's top defining a ladder top plane, the container plane and the ladder top plane in alignment and alongside each other to define an overall plane when the first protrusion of the container is engaged with the first slot of ladder top, the plurality of rails of the front section including a right front rail, said right front rail is attached to an inside of a right flange of the ladder top, the right flange disposed between and attached to the front and the rear and extends down from the periphery, the plurality of rails of the rear section including a rear right rail, said rear right rail is attached to the inside of the right flange. **40**

2. A method as described in claim 1 wherein the engaging step includes the step of engaging a second protrusion of the container with a second slot of the ladder top to hold the container to the ladder top. **30**

3. A method as described in claim 2 including the step of carrying the container by its handle up the ladder. **45**

4. A method as described in claim 3 wherein the container is a case, and there is the step of opening a first portion of the case to access the objects in a second portion of the case. **50**
